UNITED STATES PATENT OFFICE.

JOHN JERVIS, OF ST. PAUL, MINNESOTA.

SWITCH-STAND.

SPECIFICATION forming part of Letters Patent No. 340,719, dated April 27, 1886.

Application filed June 25, 1884. Serial No. 137,057. (No model.)

To all whom it may concern:

Be it known that I, JOHN JERVIS, a citizen of the United States, residing at St. Paul, in the county of Ramsey, State of Minnesota, have 5 invented a new and useful Improvement in Switch-Stands, of which the following is a specification.

In the accompanying drawings, Figure 1 is a vertical view of the switch stand, looking 10 across the track. Fig. 2 is a side view of the same, showing the operative parts. Fig. 3 is a plan view in cross-section through the line xx , Fig. 1. Fig. 4 is a plan view of the lever-wheel, with certain parts of the switch-stand 15 omitted.

The switch-stand is constructed of removable parts, with a top plate, D, and base-plate C, connected together by four uprights or legs, E. The legs E consist of rods e, inclosed in 20 gas-pipes, which form sleeves d, and serve to keep the plates C D equidistant. The rods are secured to the plates in any suitable manner. In the present instance they are riveted to the upper plate, D, and secured to the lower 25 plate, C, by nuts b. The sleeves d, by keeping the plates equidistant, permit the ends of the crank-shaft F to have free movement in their bearings. A crank-shaft, F, is mounted in the switch-stand, having its lower crank 30 end, G, resting in a socket, S, in plate C, and its upper end projecting through plate D. Before mounting the shaft F in position an ordinary switch-rod, H, with attaching socket J, is readily connected with shaft F by an eye, 35 T, by slipping the eye T on shaft F until it rests just above crank-arm G, thus dispensing with any securing-pin or other fastening device. The shaft F being of a curved form, as shown, in connection with its crank-arm G, 40 gives a better throw to the switch-rail. Furthermore, owing to the curved form of the crank-shaft the switch-rod can be readily slipped on and off the same in case of repair, and, being located above crank-arm G, cannot 45 become detached.

Upon the upper projecting end of the shaft F is mounted a wheel, I, which serves as the lever for throwing the switch. The wheel I is secured to the shaft F by a key, B, and is 50 provided with a locking-latch, L, mounted on a pivot, P, in suitable bearings, Q. The down-

wardly-projecting portion l of the latch L normally projects through an opening, R, in wheel I, and its end rests against and slides upon the plate D when the lever is operated. The 55 opening R serves as a brace for the latch L and removes the strain from its pivot-bearing.

Upon the periphery of the plate D are slots or notches M, with which the nose l of the latch L engages and locks the lever in position. It will be seen by this construction that the latch L operates automatically to lock the switch, and does not require any manipulation by the switchman, except to raise the nose l out of the slot M to unlock the switch. 65

If it should be desired to make several throws of the switch in succession without locking it, the latch L can be thrown clear back out of the way, its outer end resting against the target-staff. The target-staff O has a sleeve, K, 70 screwed on its lower end, into which sleeve projects the upper end of shaft F, which is secured thereto by a bolt, a, thus uniting shafts O and F together.

N N N indicate in dotted lines in Fig. 3 the 75 different positions occupied by crank-arm G.

By employing the wheel-lever I, directly connected with the target-shaft, and crank-shaft operating the switch-rod, the advantages 80 of this improvement will be seen at once.

The device is simpler, less liable to get out of repair, is stronger, and has greater resisting-power.

The lever may be operated at any side of the 85 switch-stand in an emergency.

In case of repair the parts, being easily detachable, may be readily replaced.

What I claim, and desire to secure by Letters Patent, is—

1. The combination, with the switch-rod, of 90 the vertical curved crank-shaft, the switch-rod adapted to be slipped on and off of the crank-shaft above its crank-arm, substantially as described.

2. The combination, with the curved crank-shaft having the lever-wheel mounted thereon, carrying the automatic gravity locking-pawl, of the top plate of the switch-stand, having a series of slots with which the locking-pawl engages, substantially as described. 95

3. The combination, with the vertical crank-shaft, curved as shown and described, of the 100

target-staff detachably connected thereto, substantially as described.

4. The combination, with the switch-stand constructed with removable parts, of the curved vertical crank-shaft having the switch-rod removably connected thereto by a sliding connection above the crank-arm of the vertical shaft, substantially as described.

5. The combination, with the top and bot-

tom plates having the ends of the vertical curved crank-shaft removably journaled therein, of the rods connecting the plates together and inclosed in sleeves, the bottom plate being removable, substantially as described.

JOHN JERVIS.
